DESIGN FOR A GIRDLE GARTER

Rosanne Linder, Upper Darby, Pa.

Application May 6, 1942, Serial No. 106,802

Term of patent 14 years

To all whom it may concern:

Be it known that I, Rosanne Linder, a citizen of the United States, residing at Upper Darby, in the county of Delaware and State of Pennsylvania, have invented a new, original, and ornamental Design for a Girdle Garter, of which the following is a specification, reference being made to the accompanying drawing, forming a part thereof.

The figure on the drawing is a perspective view of a girdle garter, showing my new design.

I claim:

The ornamental design for a girdle garter, as shown.

ROSANNE LINDER.
